UNITED STATES PATENT OFFICE.

ALFRED G. F. KUROWSKI, OF BROOKLYN, NEW YORK, ASSIGNOR TO UNDERWOOD ELLIOTT FISHER COMPANY, OF NEW YORK, N. Y., A CORPORATION OF DELAWARE.

TYPEWRITING MACHINE.

Application filed November 25, 1927. Serial No. 235,541.

This invention relates to typewriting machines which are used for typing stencils, and particularly to machines provided with frames in which stencil-cards are inserted in a flat and moistened condition. The present improvement relates to devices for shielding the machine for the purpose of protecting the slots in the segment, the ribbon-shield and operating arm, the type-bars and the link-bearings from water or other liquids used in moistening the stencils before inserting them in the machine and dirt from the stencils. Heretofore, one of the main objections to the stencil-typing machines has been the clogging up and sticking of the typewriter-parts, due to the rust and dirt caused by the wet stencils, so that it has been essential to clean the typewriter thoroughly very frequently in order to keep it in good working order. The necessity for the costly cleaning of the machine so frequently will be greatly eliminated by providing the machine with shielding devices in accordance with the present invention.

According to the present invention there is provided a longitudinal shield at the rear of the segment-bar in a position so that moisture or dirt of any kind which drops from the stencil-card will fall on the shield, and from there into an inclined gutter which directs such matter into a removable receptacle outside the frame of the machine. The shield itself is formed with a gutter extending over the universal bar and other parts of the typewriting machine in a manner to divert the fluid from these parts, so that it will flow out either side thereof into the inclined gutter. Both the shield and inclined gutter are positioned where they will not interfere in any manner with the operating parts of the typewriting machine.

The shield and gutter in accordance with the present invention are formed so as to be readily attached to the machine without altering any of the parts thereof, but by securing them in place by utilizing existing screws which secure other parts of the machine in place.

Other features and advantages will herein-after appear.

In the accompanying drawings,

Figure 1 is an isometric view of the rear portion of a typewriter, with parts broken away to show the present invention applied thereto.

Figure 2 is a rear elevational view of the typewriting machine in which the present invention is incorporated, parts being omitted and broken away.

Figure 3 is a vertical sectional view taken on line 3—3 of Figure 2.

This invention is illustrated as applied to an Underwood standard typewriting machine suitable for the handling of cards, such as used in certain types of addressing machines. The machine includes a platen 11 mounted in a carriage 12, reciprocably mounted upon a frame 13 in the usual manner. This machine is provided with a stencil-card-carrying frame 14 for carrying a stencil-card 15 in flat condition, in typing position in front of the platen 11. The usual type-bar-segment 16 is provided on which type-bars 17 are pivotally mounted at 18 and operated by means of levers 19 and 20 causing the type-heads 21 to strike along the printing line of the platen. The typewriter is provided with the usual universal bar 22 and escapement-mechanism generally designated at 23, with which the ribbon-vibrator 24 is connected for raising the ribbon 25 to the printing point when a type-key is depressed. The ribbon may be silenced for cutting stencils by a mechanism (not shown) such as disclosed in the patent to Cook, No. 926,050, dated June 22, 1909. The escapement-mechanism 23 and other parts are mounted on standards 26 extending upwardly from a base 27 mounted on the rear base-portion 28 of the frame 13. The parts thus far described are all standard in the stencil-cutting typewriting machine.

The present invention includes a shield 29, which is secured by means of screws 30 to the segment-bridge 31 and slopes downwardly therefrom with the middle portion of the lower edge bent upwardly to form a gutter 32 above the universal bar 22, extending between it and the typewriter case-shift-bar 33. The shield 29 extends laterally beyond the ends of the type-bar-segment a sufficient distance so that it will extend under the stencil-card 15 from one extreme end position of the card-frame travel to the other.

It is customary to soak the stencil-cards and position them in the card-holder in a moistened condition. The shield 29 is effective to catch any drippings, small particles of fiber or other matter from the stencils and to divert the same away from the va-

rious underlying parts of the typewriter so that the drippings will fall into an inclined gutter 34 beneath the shield 29. The gutter 32 is effective to direct such matter to either 5 side of the universal bar and ribbon-vibrating mechanism.

The gutter 34 is provided with a closed upper end 34^a and extends from the left-hand end of the shield 29 downwardly in an inclined direction to a position beyond the 10 right-hand portion of the frame 13, and on the outer end 35 thereof is a removably-mounted receptacle 36. A ring 37 is secured to the end 35 of gutter 34 and is provided with 15 bayonet slots 38 for receiving pins 39 on the receptacle 36. This receptacle 36 can be emptied by occasionally removing it from the ring 37 by a slight turn therein, and, after it is emptied, it can be returned and fastened in 20 place again by a similar operation.

The gutter 34 is provided with rearward horizontal extensions 40, 41 and 42, which are secured to similar extensions on arms 43 and 44 extending upwardly from a base-member 25 45, which is secured above the escapement-base 27 by means of screws 46. The extensions 41 and 42 are separated sufficiently so as not to interfere with the back-spacing link 47 of the typewriting machine, which extends 30 upwardly through an opening 48 provided by the spacing between the extensions and formed in the upper portion of the arm 44.

Variations may be resorted to within the scope of the invention, and portions of the 35 improvements may be used without others.

Having thus described my invention, I claim:

1. In combination with a typewriting machine for cutting stencil-cards, including a 40 platen and a card-frame for carrying stencil-cards in typing position in front of the platen, a shield secured to the machine of such a length as to extend under the entire length of the card in any typing position of the card-frame, and a gutter extending under said 45 shield to receive liquid and waste-matter falling from said shield to carry the same to the outside of the machine.

2. In combination with a typewriting machine for cutting stencil-cards, including a 50 platen and a card-frame for carrying stencil-cards in typing position in front of the platen, a shield secured to the machine extending under the card in the frame so as to 55 receive liquid and waste falling from the stencil-card in any typing position of the carrying frame, a gutter formed at the lower edge of the shield extending over the operating parts of the machine to divert the liquid and waste-matter to either side to prevent it 60 from falling on said parts, a second gutter extending under said shield to receive said liquid and waste-matter falling from the side portions of said shield, and means to support 65 said second gutter in an inclined position so

that the gutter will carry said liquid and waste-matter to the outside of the machine.

3. In combination with a typewriting machine for cutting stencil-cards, including a platen and a card-frame for carrying stencil-cards in typing position in front of the platen, a shield secured to the machine extending under the stencil-card in the frame so as to receive liquid and waste falling from the stencil-card in any typing position of the carrying frame, a gutter formed at the lower edge of the shield extending over operating parts of the machine to divert the liquid and waste-matter to either side to prevent it from falling on said parts, a second gutter 70 extending under said shield to receive said liquid and waste-matter falling from the side portions of said shield, means to support said second gutter in an inclined position so that the gutter will carry said liquid and waste- 75 matter to the outside of the machine, and a removable receptacle at the lower end of said second gutter for receiving the liquid and waste-matter.

4. In combination with a typewriting machine for cutting stencil-cards, including a platen and means for carrying a stencil-card in typing position in front of the platen, a shield secured to the machine so as to extend under the stencil-card, and a gutter extending 80 under said shield to receive liquid or waste-matter falling therefrom to carry the same to the outside of the machine.

5. In combination with a typewriting machine for cutting stencil-cards, including a platen, a universal bar and ribbon-vibrator-actuating mechanism extending forwardly and rearwardly under the platen, a stencil-card-carrying frame reciprocably movable with the platen, a shield secured to the machine extending under the lower edge of said frame and to either side sufficiently to extend beyond the ends of said frame in any typing position thereof with respect to the printing point of the machine, and a gutter formed on the lower edge of said shield extending over said universal bar and ribbon-vibrating mechanism to divert liquid and waste-matter falling on these parts.

6. In combination with a typewriting machine for cutting stencil-cards, including a platen, a universal bar and ribbon-vibrator-actuating mechanism extending forwardly and rearwardly under the platen, a stencil-card-carrying frame reciprocably movable with the platen, a shield secured to the machine extending under the lower edge of said frame and to either side sufficiently to extend beyond the ends of said frame in any typing position thereof with respect to the printing point of the machine, a gutter formed on the lower edge of said shield, extending over said universal bar and ribbon-vibrating mechanism to divert liquid and waste-matter falling on these parts, and a second gutter ar- 115 120 125 130

ranged under said shield in an inclined position to receive the liquid and waste-matter falling therefrom to carry said matter to the outside of the machine.

- 5 7. In combination with a front-strike type-writing machine, including a platen, a type-bar-segment on which type-bars are pivotally mounted, operating parts extending forward-
ly and rearwardly under the platen, and a
10 frame for carrying stencil-cards in flat condition between the platen and said type-bar-segment, a shield secured to the machine be-
tween said type-bar-segment and the card-
frame extending downwardly and under the
15 edge of the card-frame to divert liquid and
waste-matter falling from the stencil-cards
away from the type-bar bearings, and a gutter
formed on the lower edge of said shield to
prevent such matter from falling on said
20 operating parts under the platen.
8. In combination with a front-strike type-
writing machine, including a platen, a type-
bar-segment on which type-bars are pivotally
25 mounted, operating parts extending forward-
ly and rearwardly under the platen, and a
frame for carrying stencil-cards in flat condition
between the platen and said type-bar-
segment, a shield secured to the machine be-
30 tween said type-bar-segment and the card-
frame extending downwardly and under the
edge of the card-frame to divert liquid and
waste-matter falling from the stencil-cards
away from the type-bar bearings, a gutter
35 formed on the lower edge of said shield to
prevent such matter from falling on said
operating parts under the platen, a second
gutter arranged under said shield to receive
the liquid and waste-matter falling there-
from to carry said matter to the outside of
40 the machine, and a bracket-member secured
to the rear portion of the machine to support
said second gutter in an inclined position.
9. In combination with a typewriting ma-
chine for cutting stencil-cards, including a
45 typewriter-frame, a platen, a card-frame for
carrying stencil-cards in typing position in
front of the platen, and escapement-mech-
anism mounted on the rear of said typewriter-
frame, a gutter extending below the platen
50 and card-frame for receiving liquid and
waste-matter falling from the stencil-cards,
a support for said gutter mounted on said
typewriter-frame and surrounding the es-
capement-mechanism-mounting on the rear
55 of the typewriter-frame, and means for se-
curing said gutter to said support to hold the
gutter in an inclined position with its lower
end projecting outwardly through a side wall
of the typewriter-frame.
